UNITED STATES PATENT OFFICE.

CLARENCE H. WINSHIP, OF SUNRISE, WYOMING.

FOLDING AX.

1,074,764.

Specification of Letters Patent.

Patented Oct. 7, 1913.

Application filed December 14, 1912. Serial No. 736,744.

To all whom it may concern:

Be it known that I, CLARENCE H. WINSHIP, a citizen of the United States, residing at Sunrise, in the county of Laramie and 5 State of Wyoming, have invented certain new and useful Improvements in Folding Axes, of which the following is a specification.

This invention has for its object to provide an ax, hatchet or similar chopping tool with a foldable handle, so that the tool may be carried in the pocket, and also to provide a shield or guard for the cutting edge of the tool head when the handle is folded. 15 A further object of the invention is to provide a handle which can be readily folded and unfolded, and which is strong and rigid when unfolded.

These objects are attained by a novel combination and arrangement of parts to be hereinafter described and claimed, reference being had to the accompanying drawing, in which—

Figure 1 is an elevation of the tool with 25 a portion of one of the handle sections removed. Fig. 2 is a similar view showing the handle folded. Fig. 3 is a cross-section on the line 3—3 of Fig. 2.

In the drawing 10 denotes the head of the 30 ax or other chopping tool. The handle or helve is in two sections 11 and 12, respectively, which are pivotally connected as indicated at 13. The head is secured to the section 11 in any suitable or preferred manner. The outer end of the section 12 is 35 curved as indicated at 14 to form the grip of the handle. In the pivoted end of the section 11 is a keeper notch 15 for a sliding latch-bolt 16 carried by the section 12, where- 40 by said sections are locked together when unfolded. The section 12 has a longitudinal recess 17 in which the latch-bolt 16 is mounted. The rear end of the latch-bolt is 45 curved to conform to the curvature of the grip 14, and terminates in an enlargement 18 having a shoulder 19 and a transverse slot 20, through which latter a pin 21, carried by the grip, passes. The enlargement is shaped to come flush with the butt end of 50 the grip. The inner edge of the grip, at the butt end thereof, has a recess in which is 55 mounted a cam lever 22 which is shaped to lie flush with said edge except when it is withdrawn for a purpose to be presently described. The lever is pivoted to the grip as indicated at 23 and adjacent to the pivot,

said lever is cam-shaped and has the edge of said cam-shaped portion in contact with the shoulder 19.

From one edge of the latch-bolt 16, intermediate the ends thereof, projects a finger or abutment 24 which is adapted to lie between the free end of the lever 22 and the adjacent wall of the recess in which said lever is mounted. A spring 25 seating in a slot 26 in the latch-bolt 16 assists to advance the latter.

When the handle sections 11 and 12 are unfolded to render the tool ready for use, the forward end of the latch-bolt 16 seats in 70 the notch 15, and the lever 22 is folded into the grip portion 14 of the section 12 flush with the edge thereof. In this position the cam edge of the lever is in contact with the shoulder 19, and the finger 24 is between the 75 free end of the lever and the adjacent wall of the recess in which said lever is mounted, whereby the latch-bolt is held in locking position and prevented from being accidentally retracted to unlock the handle sections. 80

To unlock the handle sections, the lever 22 is swung out of the recess in the grip 14, whereupon its cam edge rides over the shoulder 19, and thereby forces the latch-bolt 16 rearward and thus retracts it from the notch 85 15. The handle sections are now unlocked, and the section 12 may be swung over toward the cutting edge of the head 10 far enough for said edge to enter the recess in which the lever 22 is mounted, said lever being left outside said recess and placed against the outer end of the head 10, where it is held by the action of the spring 25, which forces the shoulder 19 against the cam edge of the lever and thereby tends to 90 swing the lever against the outer end of the head. Thus the parts are held in folded position, and a guard for the cutting edge of the head is had, so that the tool may be carried in the pocket without danger of unfolding. 95 100

The handle section 12 carries a cover plate 27 for the recess 17 and the parts mounted therein.

I claim :

1. In a tool, a handle having a foldable section provided with a recess in which the cutting edge of the tool-head seats when said section is folded, a latch-bolt for locking the foldable section in unfolded position, and a cam lever carried by the foldable section and engageable with the latch-bolt for re- 110

tracting the same, said cam lever being mounted in the aforesaid recess and adapted to be swung out of the same to engage the tool-head when the edge thereof is seated in said recess.

5. In a tool, a handle having a foldable section provided with a recess in which the cutting edge of the tool-head seats when said section is folded, a slidable spring-actuated latch-bolt for locking the foldable section in unfolded position, said latch-bolt having a shoulder, a cam-lever carried by the foldable section and engageable with the aforesaid shoulder for retracting the latch-bolt, 10 said cam-lever being mounted in the aforesaid recess and adapted to be swung out of the same to engage the tool-head when the edge thereof is seated in said recess.

15. In a tool, a handle having a foldable section provided with a recess in which the cutting edge of the tool-head seats when said section is folded, a latch-bolt for locking the foldable section in unfolded position, said latch-bolt having an abutment, and a 20 cam lever carried by the foldable section and engageable with the latch-bolt for retracting the same, said cam lever also engaging the abutment for locking the latch-bolt in advanced position, and said cam lever being 25 mounted in the aforesaid recess and adapted to be swung out of the same when the edge of the tool-head is seated in said recess.

30. In a tool, a handle having a foldable section provided with a recess in which the cutting edge of the tool-head seats when said 35

section is folded, a slidable spring-actuated latch-bolt for locking the foldable section in unfolded position, said latch bolt having a shoulder and an abutment, and a cam lever carried by the foldable section and engageable with the shoulder for retracting the latch-bolt, 40 said cam lever also engaging the abutment for locking the latch-bolt in advanced position, and said lever being mounted in the aforesaid recess and adapted to be 45 swung out of the same to engage the tool-head when the edge thereof is seated in said recess.

5. In a tool, a handle comprising a section to which the tool head is rigidly secured, 50 and a grip section, said sections being pivotally connected to permit folding of the grip section toward the tool head, the grip section having a recess into which the cutting edge of the tool head seats when said 55 section is folded, a latch bolt for locking the handle sections in unfolded position, and a spring-actuated lever carried by the extremity of the grip section and having means for retracting the latch bolt, said spring-actuated lever being engageable with the outer 60 end of the tool head when the grip section of the handle is in folded position to receive the cutting edge of the tool head.

In testimony whereof I affix my signature 65 in presence of two witnesses.

CLARENCE H. WINSHIP.
